UNITED STATES PATENT OFFICE.

WALTHALL R. SMITH, OF NAPA, CALIFORNIA.

DESIGN FOR A HAIR-PIN.

SPECIFICATION forming part of Design No. 34,990, dated August 27, 1901.

Application filed July 27, 1901. Serial No. 69,992. Term of patent 14 years.

● *To all whom it may concern:*

Be it known that I, WALTHALL R. SMITH, a citizen of the United States, and a resident of Napa, in the county of Napa and State of California, have invented and produced a new and original Design for a Hair-Pin, of which the following is a full, clear, and exact description.

Reference is to be had to the accompanying drawings, forming a part of this specification, in which similar characters of reference indicate corresponding parts in all the figures.

Figure 1 is a face view of a hair-pin, showing my design. Fig. 2 is an edge view of the same, and Fig. 3 is an enlarged sectional plan view of the same on the line 3 3 of Fig. 1.

The design in its entirety consists of the shanks A A', connected with each other by an ornamental end A², the free end of the shank A appearing with a longitudinally-extending V-shaped ridge A³, fitting the corre-

spondingly-shaped recess A⁴ in the free end of the other shank A.

The leading feature of the design consists in the connected shanks, of which one has its free end formed with a longitudinally-extending V-shaped ridge and the other has its free end formed with a corresponding recess located opposite the ridge.

Having thus described my invention, I claim as new and desire to secure by Letters Patent—

The design for a hair-pin, as herein shown and described.

In testimony whereof I have signed my name to this specification in the presence of two subscribing witnesses.

WALTHALL R. SMITH.
